UNITED STATES PATENT OFFICE

2,661,924

CANOPY HOLDER

Melvin Charles Wilt, Hinsdale, Ill., assignor to
Curtis Lighting, Inc., Chicago, Ill., a corpora-
tion of Illinois

Application July 6, 1949, Serial No. 103,246

2 Claims. (Cl. 248—345)

1

This invention relates to supports for hanging fixtures and it relates particularly to the construction forming a part of a hanger for lighting fixtures.

Fixtures of the type described, which are suspended from the ceiling, are usually provided with a canopy that covers up the opening through which connection is made between the hanger rod and the ceiling. It is desirable to have a system whereby the canopy may be easily and quickly secured in its position of use and it is also desirable at the same time to insulate the canopy from the hanger rod.

It is an object of this invention to provide a new and improved construction permitting the canopy to be easily and quickly secured in its position of use.

Another object of this invention is to provide a hanger construction including a sleeve-like member normally slidable on the hanger rod but which is adapted frictionally to grip the hanger rod and support the canopy when in position of use and it is a related object to insulate the canopy from the hanger parts.

These and other objects and advantages will hereinafter appear and for purposes of illustration but not of limitation, an embodiment is shown in the accompanying drawings in which:

Figure 1 is an elevational view partially in section of the hanger construction associated with the canopy and embodying features of this invention;

Figure 2 is a sectional elevational view taken along the line 2—2 of Figure 1;

Figure 3 is a sectional view taken along the line 3—3 of Figure 2;

Figure 4 is a fragmentary view partially in section of another modification embodying features of my invention, and

Figure 5 is a sectional view taken along the lines 5—5 of Figure 4.

As shown in the drawing, a hanger rod 10 having a screw threaded end portion 11 is carried by a hickey 12 having one horizontally disposed upper end portion 13 which rests on the upper face of the ceiling and a bifurcated horizontally disposed lower end portion 14 which is gripped between a pair of cooperating nuts 15 and 16 operating on the screw threaded end portion 11. The hickey is adapted to carry the weight of the fixture and the hanger parts associated therewith.

An opening is usually made in the ceiling or other support for the entrance of the hickey. In the event that the suspended fixture is a lighting fixture, lead-in wires may be threaded through

the opening and passed through the hanger rod 10 for connection with the lighting elements. To cover up the opening and conceal the wires and hickey, a cup-shaped canopy 17 is positioned at the upper end of the hanger rod with its outer rim in substantial engagement with the underside of the ceiling or other support. The canopy may be of any desired shape and it may be formed of metal or molded of plastics or other relatively rigid material capable of retaining shape while at the same time giving an attractive or decorative appearance.

When in its position of use, the canopy 17 is held on the hanger rod by a ferrule or retainer ring 20 formed of relatively rigid, resilient material such as metal, plastics, hard rubber and the like. The preferred materials are polystyrene, polyethylene, polytetrafluoroethylene, polyvinylidene chloride, vinyl polymers and copolymers of acetate and chloride derivatives, rubber hydrochloride, hardened material and synthetic rubbers and the like. The ferrule is formed as a sleeve-like member having an inner diameter which is slightly greater than the overall diameter of the hanger rod. The sleeve is a split sleeve having a slot 21 through one side wall. The outer wall 22 is tapered to conform generally with the contour of an annularly flanged sleeve portion 23 struck upwardly from the lower central portion of the canopy and an annular rim 24 formed all around the lower end portion of the sleeve-like ferrule, functions as a reinforcement and gripping element. The outer diameter at the upper end portion of the ferrule is calculated to be less than the diameter between walls at the lower end of the flanged portion 23 while the outer diameter at the base of the tapered portion is greater.

To effect the assembly of parts after the hickey has been connected to support the hanger rod, the canopy is placed in the desired position and then the ferrule is slid upwardly along the hanger rod and into the space between the hanger rod and the annularly flanged sleeve 23 of the canopy. As the tapered walls of the canopy and sleeve-like ferrule engage each other with increasing force, the split sleeve portion is cammed inwardly. The slotted portion permits the diameter of the ferrule to decrease until the ferrule firmly grips the hanger rod all around. Such frictional engagement between the ferrule and the hanger rod upon reaction between the tapered surfaces of the ferrule and the canopy is sufficient to position the canopy on the hanger rod in a manner to resist inadvertent displacement. This assembly is maintained until the ferrule is purposely

withdrawn by external force which may be applied to the lower rim.

Instead of first positioning the canopy and then sliding the ferrule into position, the ferrule with the canopy resting thereon may be slipped along the hanger rod until the canopy engages the underside of the ceiling whereupon additional force on the ferrule reacts in the manner described to establish the desired mounted relation. The rim 24, in addition to its function 10 as a gripping means, serves also to prevent possible passage of the ferrule through the opening between the spaced canopy and hanger rod.

The ferrule separating the hanger rod from the canopy may be formed of electrical insulating material such as the rubberlike or plastics material described to insulate the canopy from the fixture parts when used in an electrical installation.

It will be apparent that the taper of the flanged sleeve 23 is calculated to provide for greater area of contact and that the desired reaction can be secured without the taper and even without the sleeve. Without the sleeve, the reaction will be with the edge portion defining the opening in bottom wall 25, and the split cone shaped grommet 20.

In another modification shown in Figure 4, a split sleeve 26 in the shape of an inverted frustoconical section is struck to depend from the bottom wall 25 with the smallest diameter of the sleeve at the bottom being slightly greater than the overall diameter of the hanger rod 10. The sleeve is cammed into gripping relation with the hanger rod upon reaction with a rigid grommet or retainer ring 27 having an internal diameter slightly greater than the smallest outer diameter of the sleeve but less than the diameter along the major portion of the sleeve. The internal walls of the grommet may be tapered to correspond with that of the sleeve to provide for a greater area of contact when in position of use. Instead of forming the sleeve 26 integral with the canopy, it may be formed of a separate part of materials described as being suitable for the retainer ring 20 but with an abutment provided 45 on its outer wall upon which the canopy rests.

In this modification, a gripping relation to hold the parts in position of use is effected when the grommet 27 is forced upwardly upon the outer 50 wall of the sleeve 26 progressively to decrease the diameter of the sleeve until it firmly grips the

hanger rod. Upon removal of the grommet, the sleeve is able to return to its original dimension for easy sliding movement longitudinally on the hanger rod.

It will be understood that numerous changes in the details of construction arrangement and operation may be effected without departing from the spirit of the invention, especially as defined in the following claims.

What is claimed is:

1. In a suspension device having a canopy with a smooth walled apron defining a central opening through which a hanger rod extends in closely spaced relation with the walls defining the opening, a retainer for establishing a connection between the canopy and the rod comprising a ferrule of resilient material having the form of a unitary split sleeve with an internal diameter slightly greater than the overall diameter of the rod, a tapered outer wall dimensioned to range from a diameter at one end which is less than that of the opening to a dimension which is greater than that of the opening, and an annularly arranged bead on the end of larger diameter whereby upon sliding movement of the ferrule into the space between the walls defining the opening and the rod, the diameter of the ferrule is decreased to establish a gripping relation with the rod while supporting the apron on the outer surface thereof.

2. A suspension device as claimed in claim 1 in which the opening in the canopy is defined by an annular wall tapered to correspond with that of the outer wall of the split sleeve to establish a greater area of contact.

MELVIN CHARLES WILT.
